CASING FOR A CIGARETTE LIGHTER

Frank H. Stephens, Jr., Dunwoody, Ga., assignor to Scripto, Inc., Atlanta, Ga.

Filed May 17, 1972, Ser. No. 254,350

Term of patent 14 years

Int. Cl. D27—05

U.S. Cl. D48—27 R

FIG 1

FIG 6

FIG. 1 is a front elevational view of the casing for a cigarette lighter of my design;

FIG. 2 is a rear elevational view thereof;

FIG. 3 is a left end elevational view of the lighter casing shown in FIG. 1;

FIG. 4 is a right end elevational view of the lighter casing shown in FIG. 1;

FIG. 5 is a top plan view of the lighter casing shown in FIG. 2; and

FIG. 6 is a bottom plan view thereof.

The flame shield, switch and spark wheel are shown in broken lines for illustrative purposes only.

I claim:

The ornamental design for a casing for a cigarette lighter, substantially as shown and described.
